SHIPPING CONTAINER FOR HANDLING
GOODS

Robert E. Ford, Minneapolis, Minn., assignor to
Luther Ford & Company, Minneapolis, Minn.,
a co-partnership composed of Allyn K. Ford
and Robert E. Ford

Application January 18, 1935, Serial No. 2,360

3 Claims. (Cl. 229—15)

My invention relates to a shipping container for handling goods, and has for its object to provide a container wherein a given maximum number of articles may be shipped, such as 5 canned goods or bottled goods, as, for example, liquid bluing in bottles, and which may be subdivided into smaller containers carrying a smaller number of said articles.

Manufacturers generally provide a standard 10 container for shipping their goods in established quantities such as lots of two dozen, three dozen or the like. Such goods are sent to the wholesalers or distributors and by them sold to the retailer in unbroken packages. It sometimes 15 happens that small retailers do not care to put in a full-sized container because their trade does not move the goods rapidly enough to justify purchasing the quantity of goods put up in such full-sized container. In such cases in the past 20 it has been customary for distributors to break cases and repack the smaller number of such goods in a separate container. This involves inconvenience, additional expense and danger of breakage and loss.

25 It is a particular object of my invention to remedy the above-stated disadvantages by providing an original container so formed that it may conveniently be separated into two or more independent containers each complete and in 30 condition for shipping with a smaller number of articles contained therein. As, for example, in those instances where it is customary to send out cases of two dozen articles, such case can be separated into two distinct cases each containing 35 a dozen of the articles.

It is a further object of my invention to provide such cartons with double partitions across them, either across the longer or shorter dimension of the original casing, the double partition 40 being glued to top and bottom walls and to side walls, with appropriate marking on the outside so that by the use of a knife or other severing instrument the case can be cut between the two sets of walls and thus will be divided into two or 45 more independent containers each complete in itself and each ready for immediate shipment.

In carrying out my invention the cases are 50 preferably formed, as is customary, of pliable cardboard, which may be either of the internal corrugated variety or homogeneous throughout. I do not, however, limit my invention to the use 55 of cardboard, but any substance adaptable for making shipping cases which can readily be cut is available for use and is within the scope of my invention.

The full objects and advantages of my invention will appear in connection with the detailed description given herein, and its novel features are particularly pointed out in the claims.

In the drawings, illustrating forms of application of my invention,—

Fig. 1 gives a general view of a casing embodying my invention which is adapted to be cut into two independent casings. Fig. 2 illustrates said two casings resulting from the severing of the 10 complete casing by cutting, as indicated in Fig. 1. Fig. 3 illustrates a form of the device embodying a casing adapted to be cut into three independent casings. Fig. 4 shows said casings after separation. Fig. 5 shows a casing formed to be cut 15 through the longer dimension to divide it into two long and narrow casings. Fig. 6 shows this casing after division. Fig. 7 is a plan view of a preferred form of casing adapted to be separated into two independent casings with the top flaps 20 lifted, showing the manner in which the double partition walls are introduced in the casing. Fig. 8 is a longitudinal sectional view of what is shown in Fig. 7 with the top flaps in closing position. Fig. 9 is a transverse section on the line 9—9 of 25 Fig. 8.

Referring to Fig. 1, a container 10 is formed as shown in detail in Figs. 7, 8, and 9. The outer portion comprises top panels 11 and 12 carrying label matter on either side of the meeting point 30 13 of the top flaps. Similarly, the sides of the container have label portions 14 and 15 on either side of a blank portion which may be marked by an arrowed line 16. Arrows 17 and 18 may, if desired, be formed on the line 13 which marks the 35 dividing point. Cutting the outer casing along the lines 13, 16 as indicated by the arrows produces a pair of independent containers 19, 20 each embodying a labeled top portion 11, 12 and labeled side portions 14 and 15 with new ends 21 40 and 22 formed by the container partitions hereinafter described, which may be labeled if desired.

Referring to Fig. 3, a container 23 is provided with top label portions 24, 25 and 26 and side label portions 27, 28 and 29 each separated by 45 blank spaces on the top or sides respectively. In these blank spaces sets of arrows 30, 31 and 32, 33 respectively indicate dividing lines for separating the container into three independent containers. As shown in Fig. 13, openings through 50 the top flaps of any one of the forms indicated at 34, 35, 36, and 37 may be employed for admitting the knife into the space between the double partitions for severing purposes. On Fig. 3 the form of aperture designated 36 is employed.

As shown in Fig. 4 the unitary casing of Fig. 3 has been divided into three independent casings 38, 39, and 40, each provided with new faces 41, 42, and 43 which may carry label material or not 5 as desired. It will be noted that the independent casing 39 will have two new faces 42.

As shown in Figs. 5 and 6, a casing 44 similar to casing 10 of Fig. 1 is formed in accordance with the construction shown in Figs. 7, 8, and 9 10 so as to be divided the long way of the container rather than the short way. In this form top portions 45 and 46 are adapted to carry labeling material on either side of the longitudinally-extended dividing line 47 between the side flaps. 15 The side 48 of the casing is unbroken but panels 49 and 50, adapted to carry separated label material, appear on the end walls of casing 44 and sets of arrows 51 and 52 indicate the line of severance into two independent casings. These are 20 shown in Fig. 6 where the independent casings 53 and 54 each has a new side wall 55 formed of one of the double partitions of Figs. 7, 8, and 9. It will of course be clear that it is within the scope 25 of my invention to provide a shipping casing which is adapted to be divided into a greater number of independent casings than two or three as above outlined, the principle of the invention applicable to such greater number of divisions being the same as here described.

Referring to Figs. 7, 8, and 9, a shipping container of ordinary construction is formed by gluing together at its bottom, as indicated at 56, side wall flaps 57 and end wall flaps 58 of the 30 container blank to form its bottom. When fully assembled this construction provides end walls 59, 60 carrying end closure flaps 61, 62 for the top, and side walls 63, 64 carrying side closure flaps 65, 66, also for the top, the assemblage in practice being held together by a strip of tape 35 glued over one corner not shown. As ordinarily constructed a single corrugated liner strip is applied to the inside of these walls.

As best shown in Figs. 7 and 8, I provide double 40 partition members 67 and 68 meeting in a plane 45 across the center of the container as indicated at 69. These partition members are provided with bottom flaps 70, 71 which are glued as indicated at 72 to the end wall flaps 58 heretofore referred to.

50 A pair of liner members 72 and 73, formed of corrugated board, may be set, if desired, in position on either side of the double partition wall 67, 68 as shown in Fig. 8, and by dotted line in Fig. 7, so as to enclose spaces 74 and 75. Within these 55 spaces inside these liner members the articles to be shipped are packed. Usually, in practice there will be a dozen such articles in each of the container spaces 74 and 75, although a greater or less number may be provided for. The partition members 67, 68 carry top flaps 76 and 77, respectively, which are turned over the contents within the container spaces 74 and 75 as shown in Figs. 7 and 8. These flaps are shown extending less 60 than the whole distance from the partition members 67, 68 to the end walls 59, 60, and it is within the scope of my invention for them to go the whole distance or any part of the distance so long as sufficient area is exposed for gluing. The 65 side flaps 65 and 66 are turned down over the top flaps 76, 77 and are glued thereto, as indicated at 78. The end flaps 61, 62 are then laid over and glued to the side flaps 65, 66 in the position indicated in Fig. 1.

75 To get the construction of Figs. 5 and 6, it is

only necessary to reverse the position of the dividing partitions to extend the long way of the container and glue down the end flaps 61, 62 first and then the side flaps, which will provide a device adapted to be divided longitudinally. 5 Where the term gluing is used I include all well-known forms of securing for such containers, such as stitching.

The advantages of my invention will clearly appear from the foregoing description. By its 10 employment the original shipping containers will carry the maximum number of articles which normally are handled in an original container from a distributing center. This complete case, containing such maximum number of articles, 15 may be shipped entire to dealers, and in practice most often will be so shipped. However, in those instances where dealers desire a smaller number of articles than the maximum number in the standard container, the distributing center may 20 supply such smaller number without expense of packaging or danger of loss or breakage by simply severing off one of the divisible sections of the main shipping container and shipping such section containing the desired smaller number of articles direct and unchanged to the dealer desiring that number. This arrangement and the method of employing it will greatly facilitate the carrying on of business by both the manufacturer and the distributing center, will be a matter of 25 marked convenience for the dealer and will save expense in many ways.

I claim:

1. A shipping container adapted to be separated 30 into a pair of independent containers, comprising 35 a main casing adapted to hold a maximum number of articles to be shipped, a pair of partitions adjacent one another in said casing with contacting plane-surfaced walls and having integral 40 extensions glued to the bottom of the main casing, and having right-angled extensions at their tops, flaps on two opposite sides of the main casing adapted to be folded over and upon said latter extensions and glued thereto, flaps on the other two sides of the main casing glued to the 45 top of said first-named flaps, the closely adjacent edges of said last-named flaps coming in the separation plane of said partitions, whereby the walls of the casing may be severed in said separation plane to produce two independent containers 50 each embodying plane-surfaced walls on all sides and being in condition for shipping without wrapping or other protective addition.

2. A shipping container adapted to be separated 55 into a plurality of independent containers, comprising a main casing adapted to hold a maximum number of articles to be shipped, a double partition in said casing with contacting plane-surfaced walls having integral right-angled extensions glued to the bottom of the main casing and 60 having corresponding right-angled extensions in opposite directions from the separation plane of said partitions at the top, end flaps on the main casing folded into the plane of said top extensions, and side flaps overlying all said top flaps 65 and glued to all of them, whereby the walls of the main casing may be severed in said separation plane to produce a plurality of independent containers each embodying plane-surfaced walls on all sides and being in condition for shipping 70 without wrapping or other protective addition.

3. A shipping container adapted to be separated 75 into a plurality of independent containers, comprising a main casing adapted to hold a maximum number of articles to be shipped, a double parti- 75

2,098,090

tion in said casing with contacting plane-surfaced walls having integral right-angled extensions glued to the bottom of the main casing and having corresponding right-angled extensions in opposite directions from the separation plane of said partitions at the top, end flaps on the main casing folded into the plane of said top extensions, and side flaps overlying all said top flaps and glued to all of them, and indications on the

outside of the main casing marking the separation plane of said partitions, whereby the walls of the main casing may be severed in said separation plane to produce a plurality of independent containers each embodying plane-surfaced walls on all sides and being in condition for shipping without wrapping or other protective addition. 5

ROBERT E. FORD.
